(57) **CLAIM**

The ornamental design for a handle with two grips for hand tools as shown and described.

DESCRIPTION

1. Handle with two grips for hand tools

1.1 : Perspective

1.2 : Perspective

1.3 : Front

1.4 : Top

1.5 : Bottom

1.6 : Enlarged cross-section of plane 6-6 in No. 1.3

1.7 : Perspective

The characteristic features of the design lie in the shape of the angled shaft with a generally I-beam cross-section and the hand grips at respective ends; the back view is omitted because it is a mirror image of the front view; representation 1.6 is an enlarged cross-section in the plane 6-6 of representation 1.3; the design may be used with interchangeable hand tools; the broken line illustrations of representative interchangeable hand tools in reproduction 1.7 show environmental structure and are not part of the claimed design; the parts shown by means of broken lines in the representations are not part of the claimed design; the parallel thin lines in the representations illustrate contours and flat surfaces only and do not illustrate ornamentation or decoration on the product's surface.

1 Claim, 7 Drawing Sheets
